CLAIM

The ornamental design for a controller for an electronic device, as shown and described.

DESCRIPTION

FIG. 1 is a perspective view of front, top and right side of a controller for an electronic device showing my new design;

FIG. 2 is a perspective view of rear, bottom and right side thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a cross sectional view taken along line 9-9 in FIG. 3 with an internal structure omitted; and,

FIG. 10 is a cross sectional view taken along line 10-10 in FIG. 3 with an internal structure omitted.

The broken lines shown are included for the purpose of illustrating the unclaimed portions of a controller for an electronic device and form no part of the claimed design.

1 Claim, 7 Drawing Sheets
